UNITED STATES PATENT OFFICE.

ERNEST C. MOLINDER, OF SPRINGFIELD, MASSACHUSETTS.

FORCE-PUMP.

1,175,543.

Specification of Letters Patent. Patented Mar. 14, 1916.

Application filed March 20, 1915. Serial No. 15,813.

To all whom it may concern:

Be it known that I, ERNEST C. MOLINDER, a subject of the King of Sweden, residing at Springfield, in the county of Hampden 5 and State of Massachusetts, have invented certain new and useful Improvements in Force-Pumps, of which the following is a specification.

This invention relates to pumps, and more 10 particularly relates to a novel valving system for force pumps.

As a principal object, it is contemplated by this invention to provide a hollow cylindrical pump plunger in which shall operate 15 a simple valve loosely positioned therein to be directly acted upon by the fluid pumped and to be checked at predetermined limits of movement in order to control the flow of the mentioned fluid.

20 An object of equal importance with the foregoing is to construct a pumping device of the type described which shall be constructed with such regard to proportion, number and arrangement of parts as to be 25 cheaply manufactured as well as durable and efficient, in operation.

The above and additional objects which will become apparent as this explanatory 30 description proceeds, are accomplished by such means as are illustrated in the accompanying drawings, described in the following specification, and then more particularly brought out in the claims which are appended hereto and form a part of this application.

With reference to the drawings, wherein 35 there is illustrated the preferred embodiment of this invention as it is reduced to practice, and throughout the several views 40 of which like characters of reference designate similar parts: Figure 1 is a vertical section taken through a pump casing and showing the particular pump plunger comprehended by this invention at the beginning 45 of its upstroke, Fig. 2 is a similar view but illustrating the plunger at the beginning of the down stroke, Fig. 3 is a plan of the plunger, Fig. 4 is an enlarged bottom plan 50 of the plunger, and Fig. 5 is a section taken 55 transversely of the plunger valve stem looking upward at the head.

There is illustrated a pump casing 10 of the customary cylindrical form extending 60 downwardly to the fluid source and provided at its upper end with an outlet spout 65 11 and fixed arm 12 to which is pivoted as

at 13 the operating handle 14 connected with the pump plunger by means of the usual rod 15.

The pump plunger comprises mainly the 60 hollow cylinder 16 formed along its upper edge with the annular flange 17 to which there is secured by any usual fastening means 18 a spider 19 having a loose connection with the pump rod 15, it being understood of course that the plunger cylinder is of comparatively small diameter with relation to the pump casing in substantially the proportions illustrated. At the lower end of the plunger there is secured the annular 70 metallic flange 20 maintained in fixed relation to the plunger and serving to secure the flexible packing ring 21 which is positioned thereagainst by the loose metallic washer 22 so as to be readily removable, the 75 last named washer being held in place by a cap 23 which is threadedly received over the lower open end of the piston cylinder and which is also formed with an internal annular flange 24 serving as a stop to limit 80 downward movement of the valve plunger as will be hereinafter more fully described. As a limit for the mentioned valve at its opposite point of movement there is removably positioned by the fastening means 25 85 upon the flange 17, a cross arch 26 as is clearly illustrated in Fig. 3.

The novel form of plunger valve employed in this invention in connection with the pump cylinder is illustrated in two positions at its various limits of movement in 90 Figs. 1 and 2 and comprises mainly a stem 27 on which a pair of packing rings 28 and 29 contacting with the inner walls of the cylinder 16 and suitably spaced from each 95 other by washers 30 and maintained on the stem 27 by nuts 31. Suitable apertures 32 are formed circumferentially in the piston cylinder 16 below the upper flange 17 being so positioned with respect to the movements of the valve as is shown in the drawings and as will accomplish the desired operativeness of the structure as to be later set forth. Stops 33 are provided which may consist merely of rods transfixied into the 100 valve stem 27 in order to contact with the extended inner flange 24 of the lower securing cap, as previously stated.

In operation, the handle 14 is depended upon to actuate the pumping mechanism, 110 movement of the handle resulting in reciprocation of the pump cylinder 16 within the

casing 10. Upon the up strokes as illustrated in Fig. 1, the weight of the super-in-
5 cumbent water will force the inner piston
valve downwardly until its movement is
limited by the stop 33 in contact with the
flange 24, at which point the packing rings
will be below the apertures 32 and will ef-
fectually prevent dispersion of the upper
body of water into that portion of the cas-
10 ing below the main pump packing 21. Upon
the down stroke of the pump cylinder the
lower body of fluid, to escape the otherwise
resultant compression will rise through the
cylinder and force the piston valve to its
15 uppermost limit of movement in which it
is halted by the cross arch 26 as illustrated
more particularly in Fig. 2 until the aper-
tures 32 are uncovered at which time the
fluid will escape into the upper portion of
20 the pump casing 10, these processes being
repeated during successive movements of the
operating handle 14 as will be readily un-
derstood.

While in the foregoing however, there has
25 thus been illustrated in the drawings and
described in the specification such combination
and arrangement of elements as con-
stitute the preferred embodiment of this in-
vention, it is desired to emphasize the fact
30 that such minor changes in the matters of
proportion and degree may be made in later
adaptations of this device as shall not alter
the spirit of the invention as defined in the
appended claims.

Copies of this patent may be obtained for five cents each, by addressing the "Commissioner of Patents,
33 Washington, D. C."

I claim:—

1. The combination with a pump casing; 35
of a cylinder reciprocable therewithin, a
flange formed integrally with said cylinder
at the upper end thereof, a second flange
40 fixed to said cylinder at the lower end there-
of, manually operable means to actuate said
cylinder, connections between said actuating
means and first said flange, packing means
45 removably positioned against said second
flange and in contact with said casing, a
piston valve reciprocable within said cylin-
der, packing means interposed between said
valve and said cylinder, and means auto-
50 matically causing a movement of said valve
contrary to the movement of said cylinder. 50

2. The combination with a pump casing,
of a cylinder reciprocable therein, a flange
formed integrally with said cylinder at the
upper end thereof, a second flange fixed to
55 said cylinder at the lower end thereof, man-
ually operable means to actuate said cylinder,
connections between said actuating means
and the first-mentioned flange, a piston
valve reciprocable within said cylinder, and
means for causing movement of said valve
contrary to the movement of said cylinder. 55

In testimony whereof I affix my signature
in presence of two witnesses.

ERNEST C. MOLINDER.
